UNITED STATES PATENT OFFICE

BENJAMIN HAMILTON YODER, OF CHICAGO, ILLINOIS, ASSIGNOR, BY MESNE ASSIGNMENTS, TO INDUSTRIAL PATENTS CORPORATION, OF CHICAGO, ILLINOIS, A CORPORATION OF DELAWARE

TANK FRAME FOR REFRIGERATOR CARS

Application filed October 11, 1930. Serial No. 488,065.

My invention relates to a tank frame for refrigerator cars. One of the objects of my invention is to provide a tank frame to hold the tanks of a refrigerator car in position. Another object of my invention is to provide a method for the manufacture of tank frames which is economical and results in a frame of greater strength. It must be borne in mind in this connection that railroad rolling stock is subjected to unusual stresses and strains in the service and it is necessary that the ice and brine tanks of the refrigerator car be held firmly in place with a frame sufficiently strong to withstand the stresses and strains of service.

Referring now to the drawings, in which similar reference numbers refer to identical parts in several figures.

Figure 1 is a plan view of an assembled frame designed to fit over the conventional battery of four tanks found at the end of the refrigerator car.

Figure 2 is a section thru A—A of Figure 1.

Figure 3 is a front view.

Figure 4 is a section thru B—B of Figure 1.

Figure 5 is a diagrammatic view in cross-section of the end of refrigerator car showing four tanks ridged thru two hatches, the tank frame being in place at the top of the tanks.

Referring now to Figure 1: Angle iron side pieces 1 and 2 are welded to angle iron pieces 3 and 4 and channel irons 5, 6 and 7. Channel irons 5, 6, and 7 may be of rolled steel or, as I have shown them, of pressed iron or steel, being more economical to use pressed channels than rolled channels. Angle irons 3 and 4 in channels 5, 6 and 7 are welded to angle irons 1 and 2, the points of welding being indicated by numerals 8, 9, 10, 11, 12, 13, 14, 15, 16 and 17. An opening is provided in channel iron 5 as 18 and in channel iron 7 as at 19. These openings vary in shape and position, depending upon the type of brine valves with which the tanks are equipped. The purpose of openings 18 and 19 is to permit the insertion of

valve operating rods which operate the tank valves located near the bottom of each tank, the valves being so set that tanks placed in openings 20 and 21 may be operated by inserting the valve operating rod in hole 18 and tanks placed in openings 22 and 23 may be operated by inserting a valve operating rod thru opening 19.

My tank frame serves as a spacing apparatus for the top end of the battery of four brine retaining ice tanks at one end of the refrigerator car, and is utilized for the purpose of keeping the ice tanks properly spaced and firmly fixed in the car. My tank frame is so constructed as to prevent ice from falling between the ice tanks or out into the loading steps of the car when the ice is introduced through the hatch. Ample anchorage is afforded for the brine valve operating rods. My tank frame is less expensive to manufacture and install, is stronger and gives better results than the conventional wooden framework in combination with individual malleable frames for each tank. The conventional tank frame for refrigerator cars consists of two wood carlines with wood cross pieces and four malleable iron tank frames bolted to the carlines. These wood carlines become decayed or split in the surface, causing the frame to drop down in the tanks and require renewal on an average of twice during the life of the refrigerator car.

It is understood that changes in the design and construction of my tank frame may be made without departing from the spirit of my invention as defined in the following claims.

I claim:

1. A top retaining frame for a battery of brine retaining ice tanks in a refrigerator car consisting of two parallel angle irons adapted to span the width of a refrigerator car and be firmly anchored thereto in combination with angle iron and channel iron spacers for holding the brine tanks in position.

2. A top retaining frame for a battery of brine retaining ice tanks in a refrigerator car consisting of two parallel angle irons

adapted to span the width of a refrigerator car and be firmly anchored thereto in combination with angle iron and channel iron spacers for holding the brine tanks in position, with two of said channel irons being provided with openings to permit the insertion of brine valve operating rods.

3. A tank frame adapted to be placed at the top of the battery of brine retaining ice tanks in a refrigerator car consisting of two parallel angle irons with their downwardly disposed flanges directed outwardly, provided with angle iron spacers adjacent to each end with their downwardly disposed flanges facing inwardly and adapted to fit within the top of an ice tank together with three channel iron spacers, the flanges of which are disposed downwardly and adapted to fit within the top of adjacent ice tanks, said angle iron and channel iron spacers being set sufficiently far apart to permit said tank frame to fit snugly over a battery of four adjacent brine tanks, the angle iron spacers being set at a sufficient distance from each end of the angle iron parallels to permit anchorage of the angle iron parallels near the ceiling of the car, the channel iron spacers nearest the angle iron spacers being provided with openings to permit the introduction of brine valve operating rods, all of said channel iron and angle iron spacers being parallel to each other and set at right angles to said angle iron parallels, to which angle iron parallels all of said channel iron and angle iron spacers are butt-welded.

Signed at Chicago, Illinois, this 9th day of October, A. D. 1930.

BENJAMIN HAMELTON YODER.
